UNITED STATES PATENT OFFICE.

HALBERT K. HITCHCOCK, OF PITTSBURGH, PENNSYLVANIA, ASSIGNOR OF ONE-HALF
TO HITCHCOCK EXPERIMENT COMPANY, A CORPORATION OF NEW JERSEY.

PROCESS AND APPARATUS FOR MAKING SHEET GLASS.

Application filed December 12, 1922. Serial No. 606,388.

To all whom it may concern:

Be it known that I, HALBERT K. HITCHCOCK, a citizen of the United States, and a resident of Pittsburgh, in the county of Allegheny and State of Pennsylvania, have made a new and useful invention in Improvements in Processes and Apparatus for Making Sheet Glass, of which the following is a specification.

10 The invention relates to the continuous formation of sheet glass by withdrawing it vertically from a tank or receptacle, and constitutes an improvement over what is shown in my Patent No. 805,064 of Nov. 21, 1905. It also involves a modification of the structure shown in my application No. 569,000, filed June 17, 1922, such application disclosing the formation of the sheet upwardly instead of downwardly, but involving 20 the use of rolls at the outlet similar in construction and function to those of said application. The present invention involves the employment of gravity to secure the necessary feeding and stretching action 25 upon the glass sheet, as opposed to the mechanical means for drawing the sheet upwardly as disclosed in said application, and provides for turning the sheet laterally and feeding it through a horizontal leer instead 30 of carrying it through a vertical leer. The invention has for its principal objects the provision of an improved construction of the type specified wherein a flat sheet is secured with both surfaces free from marring 35 and requiring no grinding or polishing, and the provision of a construction in which the gravity feed may be regulated to give the desired thickness of glass and speed of draw. One embodiment of the invention is illustrated 40 in the accompanying drawings wherein:

Figure 1 is a partial vertical section through the assembled apparatus; Fig. 2 is an irregular transverse section on the line 45 II—II of Fig. 1; Fig. 3 is an enlarged vertical section through a portion of the construction shown in Fig. 1; Figs. 4 and 5 are detail views showing the means for mounting the rolls for radial adjustment; and Fig. 50 6 is an enlarged detail section showing the method of mounting the guide rolls and driving them.

Referring to the drawings, 1 is the forward end of the melting tank provided with 55 forehearth 2 and the gate 3 by means of

which communication may be cut off from the tank to the forehearth. The tank and forehearth are provided with suitable means for heating and a transverse flue 4 is provided immediately beneath the gate so that 60 additional heat may be supplied at this point after the gate has been closed and the operation is to be again started up. The bottom or floor 5 of the forehearth is provided with an outlet slot 6 through which the glass is 65 withdrawn which is to form the sheet.

Immediately below the slot 6 is the rolling or sizing apparatus which is preferably mounted upon a transversely movable car 7 carried by the rails 8 so that this portion 70 of the apparatus may be readily moved out of position, when desired, for repair purposes or to give better access to the portions of the construction lying above and below the car. Mounted upon the car are a pair 75 of opposing air cooled rolls 9 and 10, preferably of nichrome or Monel metal or some other heat resisting composition whose surface will not deteriorate after continued contact with the molten glass and such surface 80 is highly polished to reduce any marring effect upon the glass to a minimum. The details of construction of these rolls and the method of cooling them constitute no part 85 of my present invention, such construction being fully set forth in my pending application heretofore referred to, and it will be understood that various means might be employed for securing a uniform cooling action upon these rolls. Devices for chilling the 90 glass below the rolls are provided in the form of the water cooled members 9^a extending transversely of the glass sheet.

The rolls are preferably driven forwardly 95 at a rate corresponding to the movement of the glass through the slot, but if desired, they may be driven at a different rate of speed or may be driven in a reverse direction. The purpose is to size or form the sheet of glass to a uniform thickness 100 throughout and to impart a certain amount of cooling effect to the sheet. Such cooling action will not be sufficient, however, to impart a permanent set to the surface of the glass, the volume of glass passing between 105 the rolls being such and the temperature of the glass being such that after the sheet has passed the rolls, the heat in the body of glass itself will cause a fire finish effect upon the surface of the sheet and prevent any im- 110

pressions received upon the surfaces of the glass from the rolls from becoming permanent.

The rolls are pivotally supported at each end of said casing 11 by means of the levers 12 and 13 pivoted at 14 and 15 and engaged at their lower ends by the links 16 and 17. These links are pivoted at their lower ends to a sliding block 18 and this block is moved up and down by the rod 19 which has right and left hand threads at its two ends, the upper of which is threaded into the casing and the lower into the block. The swinging of the levers in and out gives an adjustment of the rolls 9 and 10. In order to adjust the rolls vertically, the casing 11 is provided at its four corners with lugs 20 carrying the set screws 21 bearing at their lower ends upon the angle irons 22 forming a part of the framework of the car or truck 7.

The rolls 9 and 10 are preferably driven from an electric motor 23 carried by the casing 11 and provided with a driving sprocket 24. A suitable sprocket chain 25 passes around this sprocket 24, around suitable sprockets on the ends of the rolls 9 and 10 as indicated in Fig. 3 and over the idler sprocket 26.

Immediately below the car is the chamber 27 through which the glass sheet or ribbon 28 is conducted to the entrance end of the roller lever 29. In order to guide the sheet during its movement through this chamber and also to provide an adjustable support for the sheet as hereinafter set forth, the series of guide rolls 30 are employed, such rolls extending at their ends through the side walls 31 of the chamber 27 as indicated in Fig. 6, suitable packing 32 being provided around the ends of the rolls to prevent drafts into the chamber. Alternate rolls are preferably provided with flanges 33 which serve as guides for the edges of the sheet 28 to prevent it from working out of its proper position on the rolls. A rigid metal framework 34 is mounted along the side walls 31 of the chamber 27, such framework serving to carry the bearings 35 in which the rolls 30 are mounted. These bearings are mounted for adjustment transversely with respect to the sheet 28 by means of the arms 36 formed integral with the bearings. These arms are mounted in grooves 37 in the framework as indicated in Fig. 6 and are clamped in position by means of the bolts 38 extending through the slots 39 in the arms. In this manner each roll may be adjusted in and out for the purpose more fully hereinafter set forth. Each roll is provided at one of its ends with a sprocket 40 and these sprockets are all driven from the chain 41. A transverse shaft 42 extends parallel to and adjacent the lowest roll 30 and carries at its end the sprocket around which the chain is looped

and then passed back to the drive motor 43. This motor has upon its drive-shaft a sprocket 44 which acts as the driving element of the chain 41. The chain at its upper end is looped around a sprocket carried by the end of the transverse shaft 45 and then passes around the adjustable idler sprocket 46 and the motor sprocket 44.

Immediately below the car 7 is a pair of guide rolls 47 and 48 which are driven at 75 the same rate of speed as the rollers 30. These rolls are spaced apart a distance slightly greater than the thickness of the sheet so that when the sheet is maintained in vertical position by its weight substantially no pressure will be exerted upon the sheet at any time tending to mar it, but at the same time any substantial shifting of the plate from a vertical position is prevented. These rolls are driven by a 80 sprocket chain 49 which passes around a sprocket 30^a (Fig. 6) on the uppermost one of the set of guide rolls 30, over the top of a sprocket on the end of the roll 48, across the lower side of a sprocket on the end of 85 the roll 47 and around an idler roll 50.

The speed of draw is preferably regulated by the amount of pull imposed upon the sheet by gravity. The sheet in Fig. 1 is shown as first engaging the roll 30^a, so that the sheet is entirely unsupported until it reaches this roll. If it is desired to increase the weight upon the sheet in order to increase the speed of draw, the roll 30^a is adjusted to the rear so that the sheet first engages the roll next below the roll 30^a. On the other hand, if it is desired to decrease the pulling force or gravity upon the sheet and so decrease the speed of draw and thicken the sheet, the roll just above the roll 10^a 30^a is adjusted outward until it touches the sheet. If the change in adjustment extends any considerable distance along the set of rolls, it becomes desirable to adjust several of the rolls below the point where the sheet 10^a first engages a roll so as to modify the curvature of the guideway. In this way any desired pull upon the sheet may be secured. It will be understood, however, that many alternative expedients might be employed 11^a to secure this varying point of engagement with the curved guideway, and that the invention is not limited to the use of a roller guideway, although this is the preferred form and reduces the tendency of the sheet 12^a to be marred upon engagement with the guideway to a minimum.

The cooling of the sheet after passing the rolls 9 and 10 is so regulated that when the sheet engages the first guide roll 30^a, its 12^a surface has hardened sufficiently to avoid marring although there is sufficient flexibility in the sheet to permit it to follow the curved guideway below this point. The contact of the sheet upon the first few guide 13^a

rolls is, of course, very light so that there is only a slight tendency to mark the surface of the sheet and such surface does not have to be fully set in order to avoid marking at this point. In order to regulate the temperature of the chamber 27, some heating means is preferably employed in the chamber, the means illustrated being electrical heating coils 51 embedded in the face of the wall 52. The heating coils are divided into sections so that the heat may be distributed in the chamber in any desired way. The chamber is also provided with openings 53 and gas burners 54 for supplying any additional heat required.

From the roller guideway, the sheet passes into the leer 29 which is illustrated as having a carrier for the glass consisting of a set of rolls 55 spaced at suitable distances and rotated so as to convey the sheet through the leer as it is formed. The sheet which has a slight curvature as it enters the leer is flattened as it progresses into the leer, the sheet having sufficient flexibility to permit of this flattening operation. The rolls are driven by a sprocket chain 56 which passes along sprockets on the outer ends of the rolls and around a driving sprocket on the shaft 57. The shaft 57 also carries a spur gear 58 meshing with a spur gear 59 on the shaft 42. The lower flight of the chain 56 passes around the idler take-up roller 60.

What I claim is:

35 1. In apparatus for forming sheet glass, a glass container adapted to carry a bath of glass therein provided with refractory bottom with an outlet slot therethrough, a pair of rolls adjacent said slot, means for cooling the rolls, a curved guideway below the rolls for receiving the sheet formed between the rolls and carrying it laterally, and means whereby the guideway may be adjusted so as to engage the sheet at varying distances below the rolls and so regulate the tension imposed by gravity upon the sheet.

2. In apparatus for forming sheet glass, a glass container adapted to carry a bath of glass therein provided with a refractory bottom with an outlet slot therethrough, a pair of rolls adjacent said slot, means for cooling the rolls, means for driving the rolls, a curved guideway below the rolls for receiving the sheet formed between the rolls and carrying it laterally, and means whereby the guideway may be adjusted so as to engage the sheet at varying distances below the rolls and so regulate the tension imposed by gravity upon the sheet.

60 3. In apparatus for forming sheet glass, a glass container adapted to carry a bath of glass therein provided with a refractory bottom with an outlet slot therethrough, a pair of rolls adjacent said slot, means for cooling

the rolls, and a curved guideway below the rolls for receiving the sheet formed between the rolls and carrying it laterally, the said guideway being positioned such a distance below the rolls that the surface of the sheet may harden beyond the marring point before it reaches said guideway.

4. In apparatus for forming sheet glass, a glass container adapted to carry a bath of glass therein provided with a refractory bottom with an outlet slot therethrough, a pair of rolls adjacent said slot, means for cooling the rolls, a curved guideway below the rolls for receiving the sheet formed between the rolls and carrying it laterally, such guideway being provided with a series of rollers and means for adjusting the rollers to change the curvature of the guideway and the distance below said rolls at which the sheet first engages one of said rollers.

5. The process of forming a continuous glass sheet or ribbon which consists in flowing it vertically from a bath of molten glass, passing the sheet through a cooling aperture to reduce it to a uniform thickness, permitting the glass to stretch of its own weight and engaging the sheet after it has hardened beyond the marring point and guiding it laterally into a leer.

6. The process of forming a continuous glass sheet or ribbon which consists in flowing it vertically from a bath of molten glass, passing the sheet through a cooling aperture to reduce it to a uniform thickness at a temperature such that it will fire finish from its own heat after such reduction to uniform thickness, permitting the surface of the glass to harden, and then engaging the sheet and guiding it laterally through a leer.

7. The process of forming a continuous glass sheet or ribbon which consists in flowing it vertically from a bath of molten glass, passing the sheet through a cooling aperture and rolling or sizing it to reduce it to a uniform thickness, permitting the glass to stretch of its own weight after said rolling or sizing and its surface to harden and finally engaging it and turning it laterally into a leer.

8. The process of forming a continuous glass sheet or ribbon which consists in flowing it vertically from a bath of molten glass, rolling or forming the sheet into a relatively thick sheet of substantially uniform thickness from edge to edge, chilling the surface of the glass adjacent the rolls, permitting the glass to stretch of its own weight, and finally engaging the sheet and turning it laterally into a leer.

In testimony whereof, I have hereunto subscribed my name this 14th day of Nov., 1922.

HALBERT K. HITCHCOCK
